UNITED STATES PATENT OFFICE

2,668,762

PROCESS OF PRODUCING SCREENS

Leon Rubinstein, New York, N. Y.

No Drawing. Continuation of abandoned application Serial No. 352,517, August 14, 1940. This application February 20, 1946, Serial No. 649,120

15 Claims. (Cl. 95—81)

This application is a continuation of my U. S. patent application Serial No. 352,517, filed August 14, 1940, now abandoned, entitled "Screens and Process of Producing the Same."

My invention relates to screens of various types and to various processes for producing the same. It also relates to the production of a screen-like corrugation on a gelatinous layer on a transparent base and to the use of this screen for different purposes. It still further relates to means, more explicitly, an oxidizer, for producing said screen-like corrugation and resists to be used in connection with this oxidizer.

One of the principal objects of my invention is to provide a new screen embodying a transparent base and a gelatinous layer thereon, the outer face of which is a screen-like corrugation.

Another object is to combine this screen with photographic black and white, and especially with color separation pictures in order to facilitate the manufacture of printing plates from said pictures.

Another object is to provide means, more explicitly, an oxidizer so adapted as to form simultaneously a screen on the surface of an exposed and photographically developed light sensitive emulsion of photographic material for black and white, especially for color separation pictures and color transparencies and to correct the transparency of the entire picture.

Still a further object of my invention is to use this new oxidizer for retouching photographic pictures of different kinds, for instance black and white especially color separation pictures and color transparencies produced by additive color photographic processes.

Further objects and advantages of the invention will be set forth in the following specification and in part will be obvious therefrom without being specifically pointed out, the same being realized and attained as hereinafter more particularly described or as pointed out in the claims hereof.

With the above and other objects of the invention in view, the invention consists of the novel methods and processes set forth in the claims hereof and in the novel combination of the various elements or parts thereof, and also in the novel products therein set forth and in the novel combination and use of the various constituents thereof, certain embodiments of the same being described in this specification.

In accordance with the aforesaid objects, my invention consists of the following main parts:

The first part comprises a screen embodying

a transparent base and a gelatinous layer with a screen-like pattern thereon; this screen may be used for the most diverse purposes; it is called by me a "metamorphosis" screen as it is able to change designs or the like seen through it in the most diverse ways.

The second part of my invention comprises the use of this screen for photographic purposes by embodying it in a photographic material. As in this case, the oxidizer by which the screen-like corrugation is produced effects, besides this corrugation, also a correction of the transparency of the pictures themselves, this screen is called by me a "combined screen."

The third part of my invention comprises the oxidizers used for producing the screens and the fourth comprises various resists used in combination with these oxidizers if the same are used for retouching or like purposes.

These parts of my invention will be described each separately as far as this is possible in order to facilitate the understanding of the invention by those skilled in this art.

I

In accordance with my invention, both the "metamorphosis" and the "combined" screen consist of a transparent base and a photographic layer thereon, the outer face of said layer being corrugated like a screen by treatment with an aqueous solution of at least one acid selected from the class consisting of the hydrochloric, sulphuric, nitric acid groups and their derivatives. As pointed out in the following, I prefer to use these acids in combination with other substances thus forming an oxidizer with combined effect.

The metamorphosis screen consists of a transparent base and at least one antihalation thereon, whereby the outer surface of said antihalation layer or layers is treated with said acids or with the oxidizer and thereby corrugated like a screen.

This screen-like corrugation has the appearance of a mosaic crystalline structure with innumerable minute intersections and has the characteristic of letting a picture or other object appear completely sharp if placed in contact with or very close to the screen but causing the picture or object to appear diffused if slightly removed from the screen; the difference in effect depends on the distance of the screen from the object or picture viewed through it.

The screen will furthermore have a lenticular effect when a strong light ray is impinging on it and will thus diffuse sharp light passing through it. It further possesses the power to change tex-

tures of screens viewed through it from any fine ruled or reticulated to a very fine grain screen texture.

I propose to make my metamorphosis screen by treating an antihalation layer on a transparent base with a solution containing one or more of the acids enumerated above, or especially with an oxidizer comprising said acid solution. The treatment may also be carried out only with acid or with an acid and formalin containing solution or the oxidizer mentioned above. Depending on the ingredients of the solution used for the treatment, I have to vary the time of treatment from about one to a few minutes.

I may use a transparent base with a transparent gelatinous, e. g. antihalation layer thereon or I may use a normal photographic material with the emulsion on one and the antihalation layer on the other side of the base. The process of producing is slightly different for both types of initial materials: In the first case the antihalation layer may be treated directly, while in the second case the treatment has also to include removal of the emulsion.

For producing a screen on a material without emulsion i. e. on the antihalation or other gelatinous layer directly, I propose to treat first the surface of this layer with one of the oxidizers set forth below in detail. The timing of this treatment cannot be exactly determined in advance: it depends on the composition of the oxidizer or acid solution and of the gelatinous material used.

By varying the time of treatment, it is also possible to produce different screen textures, i. e. a screen with a more close or more open texture.

After processing the layer or layers with the oxidizer, e. g. by placing it for about 1 to 8 minutes in an oxidizer bath, I treat it with a solution of special hypo having the following composition:

	Pounds
Powdered sodium thiosulphate	About $\frac{1}{2}$
Powdered sodium sulphite	About $\frac{1}{4}$
Dissolved in about 30 liquid ounces of water.	

Thereafter, I treat it with hot water in order to uncover the screen, and simultaneously remove the remnants of oxidizer and hypo, and dry the screen thus produced. I carry out this treatment for from about 1 to about 2 minutes; a longer treatment gives an unsatisfactory result as the screen gets a too open texture. I find it of advantage to rinse the layer with cold water before and/or after the hot-water treatment.

When using a photographic material with an emulsion thereon it is necessary to include in the process the step of removing the emulsion. In this case, I place the emulsion containing photographic material for a little longer time than a material without emulsion in the oxidizer, place it thereafter for about the same time in a hypo, for instance in the special hypo mentioned above, and after rinsing the film with a stream of hot water of about 120° Fahrenheit, the entire emulsion is substantially dissolved and can be removed without difficulty. I have to carry out this treatment for about $\frac{1}{2}$ to 1 minute depending whether the emulsion was photographically developed or only exposed to light. The removal can be carried out in various ways: I have found it very easy and simple to remove the emulsion by going over the base and texture of the screen with the hand. It must be noted that the emulsion may also be removed in other

known ways if the antihalation layer is protected against removal during this treatment. I am quite aware that a saturated solution of sodium hydroxide is adapted to remove completely the emulsion layer. This saturated solution will remove at the same time also the antihalation layer and therefore it is not advisable to use it for my purposes if a dry screen is to be produced. If, however, a "damp" screen is to be produced, I may use for producing such a damp screen also sodium hydroxide or another derivative of equivalent alkalines; by treating the antihalation layer with a solution of this sodium hydroxide for about 10 to 50 seconds, washing the screen thereafter in cold water and then treating it with glycerine, described below in detail, a damp screen may be produced; this screen, however, has a somewhat irregularly disposed stipple-like corrugation and is therefore not very well adapted for my purposes. I want to stress, however, that the method of producing damp screens with sodium hydroxide or the like substances forms also part of my present invention.

As set forth above, the emulsion may be removed in any conventional way; it is only of importance that the antihalation layer should be treated in accordance with my invention. After removing the emulsion and treating the antihalation layer, the material is dried and the screen is practically ready for use. It must be noted that the screen-like corrugation on the antihalation layer is formed by the combined action of the oxidizer and the hot water, the latter simultaneously removing the emulsion.

The described process of producing my metamorphosis screen shows that all kinds of discarded films which possess an antihalation layer, whether exposed or unexposed, whether still useful or not for ordinary photographic purposes may be utilized for my metamorphosis screen. When using, however, a transparent base with a transparent gelatinous, e. g. antihalation layer, on one or both sides of the base only, there is no necessity of removing the emulsion layer; thus, it is sometimes of advantage to use a special initial material for my metamorphosis screen. As special initial material I propose to use a photographic film of the usual type comprising only the usual film base with the antihalation layer thereon without an emulsion covering the other side of the base. In some cases, it is of advantage to use as initial material a special photographic film base or other transparent base having an antihalation layer on each side of the base.

I want to point out that I may use my metamorphosis screen in dry as well as in "damp" condition; in both cases, the effect of my screen is different. The "damp" condition of the screen is preferably produced by treatment with glycerine or the like. In order to preserve this "damp" condition permanently, I propose to wet the faces of the screen covered by antihalation layers with glycerine and to enclose it between two plates of glass or other transparent material with suitable masks between glass and screen edges in order to protect the screen surface from the glass, and to secure thereafter the edges of these plates together. Thus, it is possible to keep the screen permanently wetted with glycerine, i. e. to keep it in a "damp" condition.

The damp screen is advantageous for many purposes: Thus, for example, it may be used as a comparative background in retouching of separation negatives or positives or in connection

with additive color photography or with black and white fine screens or other screen-printed matter. Placed in front of an additive color screen, it changes the appearance of the previous texture to that of a fine grain screen much better and in a more brilliant manner than when used in dry condition. The color particles become more brilliant and have thus observed a silk-like appearance. The same effect may be obtained with a black and white screen or any fine printed matter.

Taking advantage of this property of my screen, I am able to use it for printing color additive pictures. In this case the screen—after complete evaporation of the water from the glycerine—is placed in front of the color transparency at such a distance that all colors of the color transparency, even of a transparency with such fine screen as a Dufay color additive screen, appear as separate grains on the screen. Placing a light sensitive black and white emulsion on the other side of the screen and exposing through the color transparency and my metamorphosis screen, the color components of the picture are printed on the emulsion without any separate color filter as each color grain acts as filter. It may also be used as a fourth printing step in present processes of three separation negatives or positives, or it may be used in the future when it will be possible to print an additive color transparency or screen on the paper base.

My metamorphosis screen may also be used in front of transparent additive color pictures on films to be projected in cinemas or the like. In this case, the dry screen is preferable. This is placed in front of the projection window of the projection apparatus at such a distance that it eliminates only the fine-ruled screen which is visible when additive color pictures are projected in the regular way without my screen. Practically, the screen will be secured to the projector itself, as mostly the distance between screen and film in the projector has to be less than one inch, for instance, about one half of an inch.

Due to the property of my metamorphosis screen which gives in some cases a completely sharp and in some cases a diffused picture of the object viewed through it, it is possible to copy or to reproduce in a photographic way photo-mechanically printed matter—regardless what type of screen is used—and to eliminate completely in the copy or reproduction the screen net of the original photo-mechanical print which is always visible on a photo-mechanically printed picture. This process may also be used if it is desired to reproduce any paintings, etchings or the like in a manner giving the impression of a very smooth surface. For this purpose, my screen is placed and fastened at such a distance from the photo-mechanical print that the picture to be copied retains all its sharpness and brilliancy although the screen net is completely eliminated, giving thereby the photo-mechanical print viewed through the screen the appearance of a regular photographic print; then the photo-mechanical print is photographed through the screen; on the photograph thus obtained no screen net is visible, it has the appearance of a normal original photographic picture. When it is desired to copy or reproduce such photo-mechanical prints, I prefer to use my screen in dry condition.

In similar way, when it is desired to copy an old photographic picture, a great deal of re-

touching work may be eliminated by using the same method as pointed out above for the copying of photo-mechanical prints. By this method of copying old photographic pictures, my screen eliminates all the small scratches and the like which are often visible on old photographs and reduces the harshness of larger stains or damaged areas if such are present on the picture.

10 My metamorphosis screen may also be used as a photographic diffuser of the type used for photographic printing purposes. Also in this case, it is advisable to use the screen in dry condition. This method of obtaining diffusion when photographically printing will greatly reduce the costs of this process, as it is only necessary to place my screen between two glass plates and a simple and inexpensive diffuser is ready for use. By placing this diffuser at different distances from the negative to be printed, it is possible to vary the diffusion effect as required.

15 I further may use my screen to create the impression of a great number of different designs using thereby, however, one initial design only. This initial design may therefore be a very simple one, for instance skeleton-like appearance, while the designs produced by my screen will be most intricate, of such softness and so complicated as to be very difficult to design by hand. This "multiplying" effect can be attained by placing my screen before a simple skeleton-like initial design and looking through the screen at this design. It is possible to use designs of whatever type, but I prefer to make my initial design by

20 drawing on white paper and photographing it on a contrasty photographic paper or diapositive material; the negative paper or diapositive photograph thus obtained shows white, respectively transparent sharply defined lines on black background. It should be noted that the lines of this drawing should be approximately from one quarter of an inch to one eighth of an inch apart so that the lines do not overlap one another unless this is desired, for instance in the middle part of the design. Due to the screen, one will have the impression of a three-dimensional picture-like design. By varying the distance of the screen from the skeleton-like initial design, it is possible to attain the impression of a varying design when looking through the screen. This effect may be used for different purposes, especially for the textile industry where it is of importance to create different textile designs at low cost, which can be easily done by photographing one or more simple skeleton-like designs through my screen, varying between the taking of the pictures the distance between screen and the skeleton-like design.

25 30 35 40 45 50 55 60 65 70 75 I want, furthermore, to stress the importance of my metamorphosis screen for television purposes where the quality of the reproduced image is influenced by the visibility of the scanning lines on the televised image. By securing a metamorphosis screen, not in contact with, but at a small distance in front of the fluorescent screen of the receiving cathode ray tube used for television purposes, it is possible to make the scanning lines on the image practically invisible when viewed through the screen, thereby giving the impression of a cinematographic continuous projection. It must be noted that this combination is of special importance for television transmission on large screens as in this case the scanning lines are especially visible; in this case, my screen may be applied with the same result as explained above in connection with the projection

of color additive pictures or it may be applied directly in front of the fluorescent screen of the picture transmitting cathode ray tube. My screen may also be used as a projection screen for televised images or for small-size cinematographic projection. One face of the screen may be silver-covered and thereby its reflecting capacity multiplied.

By using my screen, I may also produce photographic records from black and white or color televised images and eliminate all scanning lines from these photographs.

My new metamorphosis screen may also be used for all purposes for which frosted or ground glass or the like can be used: thus, its use is of advantage in headlights of automobiles, e. g. in the form of a damp double screen, or for windows of the most diverse kind. It may also be used for fancy lamp shades; in this case, I provide the lamp shades with small holes, e. g. pin holes; by illuminating the lamp shades thus prepared, I obtain an aureola effect around these holes. I may use this effect for other purposes also in order to attain aureola-like color effects, e. g. for illuminating devices for advertising means and the like. I may use my screen also for lamp bulbs and the like. It also has the effect of changing strong illuminating light to a very soft lighting effect which may be used especially in photographic studios for color photography. For this purpose, a damp screen or a double metamorphosis screen is especially well adapted. It has, furthermore, the advantage of absorbing a small, practically imperceptible part only of the light passing through it. A further advantage consists in the even and uniform distribution of the screen-forming corrugation thereby making possible an even distribution of the light passing the screen.

Summarizing, it may be seen from the above description that the production of my new metamorphosis screen is inexpensive and can be carried out easily; that furthermore the screen thus produced has a series of characteristics making it advantageous for a great number of fields in which heretofore either expensive screens have had to be used or in which it has been impossible to attain the required effects by the use of screens.

II

As set forth above, the second part of my invention comprises the use of this metamorphosis screen for photographic purposes by embodying it in a photographic material. The screen thus produced, called by me a "combined" screen, is of special importance for color photographic purposes, e. g. for obtaining color separation negatives or positives for multicolor printing purposes. Thus, this combined screen may be used for making printing plates for multicolor pictures by photomechanical means and for photographic reproduction of natural color photographs, paintings, sketches, drawings or the like.

In accordance with my invention, my combined screen comprises a transparent film and an exposed photographically developed emulsion thereon, the outer surface of which is treated with an oxidizer comprising an acid selected from the class consisting of the hydrochloric, sulphuric and nitric acid groups and their derivatives. I prefer to use an oxidizer which besides forming a screen-like pattern in and on said emulsion layer also corrects the transparency of the entire picture in a novel manner. The screen-like pattern produced by the oxidizer treatment com-

prises substantially equally disposed opaque and transparent screen portions, the opaque screen portions, being differently blackened in accordance with the light intensity reflected from respective parts of the picture taken or printed, and the transparent screen portions being substantially equally transparent throughout the entire photographic picture. It must be noted that although the transparent portions are more or less equally transparent, their transparency varies between the dark and the light picture portions; thus, in the dark picture portions the transparent screen portions are substantially grey, while in the light parts they are entirely transparent. When using my combined screen for producing printing plates, I propose first to make a black and white or color separation picture on a photographic material provided with a light sensitive emulsion, to treat thereafter the surface of said emulsion after exposure and slightly darker development, as usual with an oxidizer as set forth above in connection with my metamorphosis screen, forming thereby the described screen-like corrugation on the emulsion layer, to print thereafter photographically said screen-like picture on the light sensitive surface of a printing plate, and treat said printing plates in such a manner as to produce ink-retaining cells corresponding to the blackened screen portions, said ink-retaining cells being of substantially equal size but different depth in accordance with the different blackening of the opaque screen portions.

If great differences between the opaque and transparent screen portions are desired, I propose to use my combined screen in damp state treated with glycerine.

It is seen that my invention embraces not only the various types of my so-called metamorphosis screens but also my combined screen with the latter differing from the former by also carrying an image on the photographic emulsion film, and that while I can produce the metamorphosis screens as well as the combined screen by using one of the three acids, sulfuric, hydrochloric, and nitric, and each of them without including any iodine, I obtain an additional advantage when I include iodine along with the acid in producing my combined screen because the presence of the iodine then yields simultaneously with the formation of the screen a correction or clarification of the photographic image on the emulsion film.

As set forth above, my oxidizer is adapted not only to provide a screen-like pattern on the emulsion surface but also to correct the transparency of the photographic picture itself; thus I am able to correct the transparency of photographic black and white and especially color separation pictures and color transparencies produced by additive color photographic processes. This correcting or retouching process may be carried out either for the entire picture or for parts of the picture only. In the latter case, I coat the picture portions on said light sensitive emulsion layer which are not to be treated with a transparent resist, treat the uncoated portion of the picture with an oxidizer solution, controlling constantly the brightening of the portions treated with a densitometer, and remove thereafter the resist.

Having now described in general the different fields in which my combined screen may be used and the way in which it has to be used, I want now to proceed with a more detailed description of making my combined screen for color photo-

graphic and especially multicolor printing purposes:

I must make several, e. g. three or four, separation negatives or positives on a preferably panchromatic emulsion; thereafter I immerse each separation positive or negative in the oxidizer.

After immersing the photographic developed picture for about 4 to 8 minutes in the oxidizer, depending on the composition of the oxidizer, the photographic material, and other conditions, as temperature or the like, the photographic film is washed in cold water e. g. by dipping in a water tank or by holding it under a gentle stream of cold water, moving it preferably in a horizontal or vertical direction until the screen is uncovered. In order to obtain an even design, it is of advantage to watch the photographic material constantly, preferably with a magnifying glass. When the screen-like pattern has appeared on the emulsion surface, the film is placed in a special hypo bath, the composition of which I described in connection with the production of my metamorphosis screen. Then it is dried in cool air at about 60 to 65 degrees Fahrenheit, preferably in a dustproof place. When the screen thus produced is dry I can—if it is desired and necessary—correct the color values locally, as pointed out above.

I want to point out that the screen is produced by the combined action of the oxidizer and the cold water, and thus both process steps of treating the photographic developed image with the oxidizer and with the cold water are essential from the point of my invention. After correct processing and drying the emulsion surface assumes a glossy or silk-like appearance; the absence of this glossy appearance of the surface of the combined screen proves that the film has not been properly processed. The completely processed film remains, after drying, permanently hard, if not wetted with glycerine. The surface is so hard that wax or other impressions can be made from it without difficulty.

I want also to note that my combined screen has—besides the properties enumerated above—also practically all the characteristics and advantages of my metamorphosis screen described in the first part of the present description. Thus, it has also the appearance of a mosaic crystalline structure with innumerable minute intersections and has also the characteristics of letting a picture or other object appear completely sharp if placed in contact with or very close to the screen, but of causing the picture or object to appear diffused if slightly removed from the screen; the difference in effect depends hereby on the distance of the screen from the object or picture viewed through it. In order to make the picture or object to appear diffused, I may also use a damp screen; in this case, the degree of diffusion depends also on the patterns of the screen. In order to produce this damp screen, I place it, after the screen is somewhat dried, in glycerine and keep it thus permanently damp. After a certain time, when the water evaporates, it will remain in slightly swollen condition, permanently wetted. It will be possible to place the damp screen thus produced in direct contact with a suitable material for reproducing purposes.

The screen will furthermore also have a lenticular effect when a strong light ray is impinging on it and will thus diffuse sharp light passing through it. When imageless, it further possesses

also the power to change textures of screens viewed through it from any fine ruled or reticulated to a very fine grain screen texture.

I want to repeat and emphasize that the screen-like corrugation on the emulsion surface consists of opaque and transparent screen portions, the opaque screen portions being of substantially equal size but differently blackened in accordance with the corresponding parts of the picture taken, while the transparent screen portions are substantially equally transparent throughout the entire picture.

As pointed out above, also the transparent screen portions will vary from grey to entirely transparent in accordance with the blackening of the original image. By photographically printing this screen-patterned corrugated picture on the light sensitive surface of any metal, stone, or similar printing plate, I receive on this plate a screen-like reproduction of the original black and white picture or color separation negative, which partly looks like a plate produced by the offset-process, partly like a plate produced by the intaglio-process. This picture on the printing

plate consists of differently blackened stipple-like opaque portions of substantially equal size, the different blackening of these stipple-like opaque screen portions corresponding to the blackening of the original black and white pic-

ture or color separation negative. By treating this screen-like surface of the printing plate in such a manner as to produce ink-retaining cells corresponding to the opaque screen portions, I am able to produce a printing surface with ink-retaining cells of substantially equal size but different depth in accordance with the different blackening of the opaque screen portions. By using this printing plate for printing purposes, I receive a print with a screen-like pattern consisting of opaque and transparent screen portions; the opaque screen portions on this print are of equal shape with the ink-retaining screen portions on the printing plate, but the different depth of these ink-retaining screen portions re-

sults in different blackening of the corresponding screen portions on the print. Thus, my new process creates a print similar to prints produced by the gravure process. It is thus possible to eliminate the necessity of printing the picture which has to be reproduced on a screen, and it is also possible substantially to eliminate etching or other methods of retouching, such as dot correction of the picture to be reproduced. It must be noted that by using color separation negatives provided with different combined screens, i. e. different screen designs for superimposing and thus creating additive color pictures, these color pictures will give a much better mix of colors than known heretofore.

It must be stressed that for producing printing plates, I prefer to use separation negatives or positives with a preferably damp metamorphosis screen on the other side of the emulsion base; by using such an initial material, i. e. a film base provided with a metamorphosis and combined screen, I get a much better result than with a combined screen alone.

Those familiar with the art of photo-mechanically producing pictures will realize that by using my combined screen in the way described above, it will be possible not only to simplify the process of printing to a great extent, by omitting several steps, e. g. printing on screen and etching, but also to attain not only black and white but

also color prints of highest quality in an easy and inexpensive manner.

III

Having thus described my metamorphosis screen and my combined screen, and the way in which they are produced with the help of my new oxidizers, I want to describe in detail the composition of these oxidizers and the manner in which they are made.

I have found that I can use as oxidizer for all purposes of the character described a composition of matter comprising a substance selected from the iodine group, a substance from the group consisting of formaldehyde and other aldehydes, and at least an acid selected from the class consisting of hydrochloric, sulphuric and nitric acid groups and their derivatives, said substances being dissolved according to the different purposes for which they are to be used in water, glycerine or the like.

I have found that for producing my screens it is preferable to use an oxidizer comprising about one to two parts by volume of at least one substance selected from the group consisting of iodine tinctures and concentrated iodine solutions, about one to two parts by volume of an iodine of the decolorized iodine group, about one to two parts by volume of an aqueous solution containing about 40% formaldehyde, and about one to two parts by volume of an acid selected from the group consisting of hydrochloric, sulphuric and nitric acids and their derivatives, said iodine, formaldehyde and acid being dissolved in about 120 parts by volume of distilled water.

In order to be able to control the formation of the screen on the gelatinous surface, i. e. to vary the softness or contrasts of the screen patterns, I can add to the above described oxidizer sugar or common salt, i. e. sodium chloride. I have found that by the addition of these substances and by varying the quantity added, I am able to produce screen-like corrugations of different softness and contrasts. I have furthermore found that for local retouching purposes, in which case a strong oxidizer is needed, it is of advantage to dissolve the iodine, formaldehyde and acid not in water but in glycerine or the like, thus forming a quickly and strongly acting oxidizing solution.

In the following I describe different oxidizer solutions, which I have found to be especially advantageous for my purposes:

1. An oxidizer which has proved to be the best for substantially all my purposes consisting of—

Concentrated iodine.....	drams	1
Decolorized iodine N. F. VI.....	do	3
Formalin.....	do	1
Hydrochloric acid (or sulphuric or nitric acid).....	drams	1
Common salt or sugar.....	oz	2
Distilled water.....	oz	16

I propose to make this oxidizer by first adding to the acid half of the water and separately mixing the concentrated iodine with the decolorized iodine, and thereafter mixing the two solutions together; then the formalin and the salt or sugar are added, and the solution shaken until the salt or sugar is completely dissolved; thereafter the other half of the distilled water has to be added.

The concentrated iodine used is preferably a saturated iodine solution. I produce this saturated iodine solution by dissolving crystalline

75 iodine in 10 per cent aqueous solution of potassium iodide until this potassium iodide solution is saturated with iodine. After being filtered, this solution may be used for the oxidizer.

2. Another preferred oxidizer solution consists of—

Concentrated iodine solution.....	drams	1
Decolorized iodine N. F. VI.....	do	3
Formalin.....	do	3
Hydrochloric acid (or sulphuric or nitric acid).....	drams	2
Common salt or sugar.....	oz	2
Distilled water.....	oz	16

15 I prefer to use this solution for extremely dense color transparencies where no white objects are evident.

I prefer to make this oxidizer by mixing the concentrated iodine with half of the water and mixing separately the decolorized iodine with the formalin, and mixing thereafter the two solutions together; thereafter the acid and the salt or sugar are added and the solution is shaken until the heavy particles in the solution disappear and the solution becomes clear. Then the second half of the water is added. No filtering is necessary thereafter, the oxidizer is ready for use.

I want to stress that the oxidizer solutions described above are the most preferred; these oxidizers are made with concentrated iodine solution, prepared as above referred to and I have found that this concentrated iodine is the most preferable for my oxidizers.

3. For color transparencies, I prefer to use an oxidizer solution comprising—

Tincture of iodine U. S. P.....	drams	3
Decolorized tincture of iodine N. F. VI.....	drams	3
Formalin.....	do	1 to 3
Hydrochloric acid (or sulphuric, nitric or other equivalent acids).....	drams	2
Distilled water.....	oz	16

45 If this solution is to be used on paper prints, two ounces of common salt or sugar should be added, except when using nitric acid, in which case salt or sugar should not be added. I propose to make this oxidizer by first placing the acid in a bottle and slowly pouring into this bottle the distilled water, then mixing this acid solution with the tincture of iodine, the decolorized iodine and the formalin, and adding thereafter the second half of the water. No filtering is necessary.

4. For the same purpose I can use also an oxidizer solution comprising—

Tincture of iodine U. S. P.....	drams	3
Decolorized tincture of iodine N. F. VI.....	drams	3
Formalin.....	do	1 to 3
Hydrochloric acid (or sulphuric, nitric or other equivalent acid).....	drams	1
Distilled water.....	oz	7

For use on paper prints or in order to produce softer color effects, about 1 ounce of salt may be added, except when using nitric acid for the oxidizer. I prefer to produce this oxidizer solution by first mixing the iodines with the formalin and then adding to the mixture thus produced the water; after this solution is filtered, first the acid and then the salt are added.

5. Another oxidizer solution found to be very useful comprises—

Tincture of iodine U. S. P.....	drams	3
Decolorized tincture of iodine N. F. IV.....	drams	3

Formalin	drams	1 to 3
Hydrochloric acid (or sulphuric, nitric or other equivalent acid)	drams	1
Distilled water	oz.	7

This oxidizer is prepared in substantially the same way as the above described.

6. As a soft oxidizer working very well on color transparencies and on prints, I prefer to use an oxidizer comprising—

Iodine test solution (T. S. U. S. P.)	drams	2 or 3
Potassium iodide test solution (T. S. U. S. P.)	drams	1
Sulphuric acid (or hydrochloric, nitric or other equivalent acid)	drams	1
Distilled water	liquid oz.	7

7. Another also well-working oxidizer comprises—

Iodine test solution (T. S. U. S. P.)	drams	1 1/2
N. F. IV decolorized iodine	do	1 1/2
Hydrochloric acid (or sulphuric or nitric acid)	drams	1
Tincture of iodine (U. S. P.) alcohol 83%	drams	2
Formalin	do	2
Distilled water	oz.	14

I prepare this oxidizer by first mixing the iodine test solution with half of the water, adding to this solution the decolorized iodine, the acid, the potassium iodine test solution, the tincture of iodine and the formalin, and adding thereafter the rest of water. This solution works very well, but becomes decolorized within about 6 to 10 days, i. e. cannot be further used. If it becomes decolorized, iodine test solution may be added and thereby the solution revived to its former strength.

8. Another very useful but not durable oxidizer solution consists of—

Churchill's tincture of iodine, N. F. alcohol 62%	drams	1/2
Decolorized tincture of iodine N. F. IV	do	1
Formalin	do	1
Hydrochloric acid (or sulfuric or nitric acid)	drams	1
Common salt or sugar	oz.	1
Distilled water	oz.	14

9. Still another oxidizer adapted for my purposes consists of—

Solution iodine compound (Lugol) U. S. P.	drams	1
Decolorized tincture of iodine N. F. VI	drams	2
Formalin	do	2
Hydrochloric acid (or sulphuric or nitric acid)	drams	2
Distilled water	oz.	14

In the preceding illustrative examples there are included specific amounts of certain respectively individually designated iodine solutions, the particular constitution and preparation of which follows:

(a) *Decolorized iodine N. F. VI* is prepared by addition to a solution of 25 grams of potassium iodide in 400 cc. of water of 50 grams of iodine and 400 cc. of alcohol and stirring. After the iodine is completely dissolved, 100 cc. of stronger ammonia water (about 37% NH₃) are added and the mixture allowed to stand until it becomes

colorless. Thereafter sufficient alcohol is added to bring the volume to a total of 1,000 cc.

(b) *Decolorized iodine N. F. IV*.—Digest 83 grams each of iodine and sodium thiosulphate in 100 cc. of water, at a gentle heat, until complete solution results. Then add 125 cc. of alcohol and afterwards 65 cc. of stronger ammonia water (37%). Shake the mixture a few minutes until bubbles of gas no longer escape, and the liquid has become colorless with a white precipitate suspended in it. Now cool the mixture, and then add sufficient alcohol to make the product measure 1,000 cc. Place the bottle containing the liquid in a cold place for a few hours and then filter. Preserve in a well-stoppered bottle.

(c) *Tincture of iodine U. S. P.*.—Dissolve 70 grams of potassium iodide in 50 cc. of distilled water contained in a bottle graduated to 1,000 cc.; add 70 grams of iodine and agitate the mixture until solution is effected. Then add sufficient alcohol to make 1,000 cc., and mix thoroughly.

(d) *Iodine test solution U. S. P.*.—Dissolve 1 gram of iodine and 3 grams of potassium iodide in 500 cc. of distilled water.

(e) *Churchill's tincture of iodine N. F.* is an alcoholic solution of iodine and potassium iodide containing not less than 16 grams and not more than 17 grams of iodine and not less than 3 grams and not over 4 grams of potassium iodide in each 100 cc.

(f) *Lugol's solution iodine compound U. S. P.* is the standard U. S. Pharmacopoeia solution containing in each 100 cc. not under 4.5 grams and not over 5.5 grams of iodine and not under 9.5 grams and not over 10.5 grams of potassium iodide.

I want to stress that for retouching purposes or for correcting only the transparency of a photographic picture without forming a screen thereon, all of the above described oxidizers may be used without the addition of acid. In this case, however, the oxidizer is only adapted for immediate use but will not be durable as a stock solution. By addition of the acid, it may be made durable for practically unlimited time. The oxidizer may be used immediately after addition of the acid, but I prefer to use it only about 5 to 7 days thereafter.

As set forth above, my oxidizer is adapted for correcting the transparency of the entire picture; this is of great importance in case of color transparencies. Due to various causes, a veil is formed even upon the most correctly exposed and properly processed color transparencies made by additive color processes. This veil prevents the transparencies from appearing to the observer in the natural colors, falsifying thereby the colors to a certain extent and giving the transparency a more or less flat and blurred appearance, especially if the transparency is slightly under or over exposed. The same veil can be found also on normal black and white or color separation pictures.

By my new oxidizer it is possible to eliminate this veil. The oxidizer is adapted to work also as reducer (in the photographic sense as to the intensity of the precipitated silver, as opposed to the purely chemical sense), if this is required and advisable.

It is not advisable to carry out the process of oxidation in strong daylight, as the oxidizer becomes less active in such light. The length of time to hold the color transparency in the

oxidizer bath is generally from about 1 to 5 minutes, depending on the density of the transparency. I have found that by holding the color transparency in the oxidizer bath a grey tinge is formed on the surface of the transparency; this tinge disappears after the hypo treatment. In preparing the oxidizer bath, it is necessary to add water only if the solution is used soon after it has been prepared. If it is about 1 or 2 weeks old, usually no addition of water is necessary.

My oxidizer also may be used for a novel method of local color correction by oxidation which comprises the steps of coating the picture portions of the emulsion which are not to be corrected with a transparent resist, immersing the emulsion in an oxidizer bath of the type described, thereby correcting the uncoated parts of the picture, and, after bathing the picture in a special hypo as described above, removing the resist from the emulsion. I want to note that I may cover the parts not to be treated with the oxidizer either by coating them with a resist in the usual manner or by applying the resist with an air brush; in the first case I will obtain a sharp outline between the treated and untreated image portions, while in the latter case I will obtain a soft merging edge portion between these image parts. In this way, it is possible to correct picture parts of color transparencies. If it is desired to make one or the other color lighter, this can also be done by this process.

Using this process for color separation negatives, I can correct one or the other part of one of the negatives, thereby correcting the final picture attained after combination of the color separation negatives. For such color separation negatives it is preferable to use a solution which is at least a few weeks old and to use this solution without addition of water as this kind of negative needs a stronger treatment. The oxidizer solutions made with decolorized tincture of iodine N. F. IV are the most satisfactory for this purpose. The action of the oxidizer on glossy and on mat papers is different; if glossy paper prints are treated with the oxidizer they remain absolutely clear during processing while mat paper prints are covered with a grey veil through the entire picture. This veil disappears by the hypo treatment.

As set forth above, it is also possible to treat photographic prints with my oxidizer and to obtain thereby satisfactory effects; my new oxidizer is especially adapted for treatment if it is necessary to regulate the contrast or softness of the prints produced in this way. The normal time of treatment is about 1 to 3 minutes depending on the characteristics of light sensitive paper used and on the density of the printed picture. For prints it is advisable to use stock solutions which are a few weeks old and which contain salt or sugar, except when a solution containing nitric acid is used, in which case no salt or sugar is to be added. It is not advisable to dilute this stock solution or even fresh ones; in diluted state it will not be durable.

I may also use my oxidizer for retouching small parts of pictures, e. g. for removing or lightening dark spots, such as blemishes, freckles, wrinkles, and the like on black and white and color separation pictures or on color transparencies.

If any of the oxidizer solutions described above were to be used for this local retouching, practically no result would be obtained, as these oxidizer solutions are too weak and work too slowly.

I therefore propose to use for this purpose an oxidizer solution comprising—

	Drams
5	Concentrated iodine or tincture of iodine
	U. S. P. alcohol 83%----- 1
	Decolorized tincture of iodine N. F. IV----- 3
	Formalin----- 1
	Hydrochloric acid----- 1
10	Glycerine (to be added before using).

The components of this solution have to be dissolved in glycerine before the oxidizer is used. If the acid and formalin are omitted from this composition, this local oxidizer decomposes quickly and lasts only a short time, but if composed as above described, it will keep indefinitely, even without addition of glycerine. The addition of glycerine greatly increases the life of the local oxidizer, even when standing in an open vessel ready for use.

This oxidizer has a very strong effect and is to be applied very gently, as otherwise it will make holes in the photographic material. It is not necessary to rub with the brush while applying the oxidizer, as every touch gives almost immediately a retouching result. Immediately after observing that the applied local oxidizer has had the required result, the spot to which the oxidizer has been applied has to be treated with a strong hypo. It is important to avoid touching other places with this hypo. After applying the hypo, the retouched photographic picture has to be washed thoroughly. I want to note that when larger areas are to be treated with my oxidizer for retouching purposes, it is advisable to first cover this area with a glycerine water mixture and to carry out the retouching within this area thereafter.

The above description of my new oxidizers and of the processes for correcting the transparency of entire photographic pictures or local large areas, where resists are used, and for retouching small spots on photographic pictures by these oxidizers, shows clearly the advantages of these oxidizers and the processes when compared with the means and methods known and used heretofore for these purposes. My new oxidizers are always ready for use, inexpensive in preparation, and adapted for all the purposes enumerated above.

IV

The fourth part of my invention relates to various new resists to be used in combination with my new oxidizers.

I propose to use as resist a composition of matter comprising a transparent substance selected from the group consisting of waxy and resinous substances dissolved in a transparent liquid solvent for said substance. This resist may be produced either as a quick-drying or as a non-drying resist. It may also be made as a transparent or as an opaque resist.

My quick drying transparent resist comprises preferably Canada balsam and benzol. If it is to be applied in the usual way, I propose to dissolve one part by volume of Canada balsam in about 8 parts by volume of benzol or another solvent for said Canada balsam. If it has to be applied with an air brush, it is advisable to use a solution comprising one part Canada balsam dissolved in about 12 to 16 parts of benzol.

My non-drying transparent resist preferably comprises wax, lanolin and white petrolatum. A

preferred composition for this non-drying resist consists of—

	Grams
Wax, white or yellow, preferably white	1
Lanolin (wool fat)	2
White petrolatum	Between 12 and 15

If a non-drying opaque resist is desired, I can include in the above described non-drying transparent resist solution Indian red pigment or white lead carbonate or other substances making it opaque.

As a drying opaque resist, the following composition may be used:

	Ounces
Beeswax	4
Oil of turpentine	18
Asphalt varnish (of Elmer and Amend make)	1
Red pigment	About 14
White lead carbonate	About 1

This opaque resist cannot be washed off with cold water; hot water, however, can be used for removing it.

I may use these resists for the most diverse purposes:

One of the principal purposes of my new resists is to cover a part of a picture during oxidation, thereby holding back the action of an oxidizer on this part while other parts are left uncovered and may be processed with the oxidizer in any way desired. My new resist is especially adapted for this process as it is transparent and thus it is possible to compare during processing the parts to be treated with the parts remaining untreated and thereby to regulate the timing of treatment as necessary. Another purpose of my resist consists in covering a part of a picture while the adjacent part is retouched, e. g. removed. Still another field in which my resist can be used is to cover pictures or paintings, retouched with an air brush, with it; if my transparent quick-drying resist is used, such a resist layer preserves the paint from being rubbed or washed off and adds a great deal to the brilliancy of the picture; furthermore, it preserves the paintings from cracking or discoloration. My new quick-drying resist may also be used for plates or films for natural color transparencies; in this case an extremely thin layer of non-drying transparent resist has to be applied to the color screen under the light sensitive emulsion. My opaque quick-drying resist has substantially the properties of a transparent resist as described above.

My non-drying transparent resist has the property of resisting acids. It also remains in a non-drying condition while the photographic film or plate is being processed; this expedites the whole process as the resist can be easily and quickly applied and after processing also be easily and completely rubbed off when the film or plate has dried and the resist is no longer needed. This non-drying transparent resist can be used also on prints to cover certain parts if it is desired to process other uncovered parts.

Having thus described the different parts of my invention, viz. the metamorphosis and combined screens, their characteristics and the processes for their production, and having also described in detail my new oxidizers and resists used for these purposes, and also the processes by which these oxidizers and resists are produced and the manner in which they may be made, I want to stress that numerous modifications and adaptations of the embodiments of my invention

described above could be made without departing from the scope of my invention.

Without further analysis, the foregoing will so fully reveal the gist of this invention that others can by applying current knowledge readily adapt it for various applications without omitting certain features that from the standpoint of prior art, fairly constitute essential characteristics of the generic or specific aspects of this invention, and, therefore, such adaptations should and are intended to be comprehended within the meaning and range of equivalence of the appended claims.

What I claim is:

1. Process for manufacturing a screen which comprises the steps of wetting a photographic material consisting of a gelatinous antihalation layer and a gelatinous photographic emulsion layer that is more easily soluble than said antihalation layer, on a transparent base with an aqueous solution containing iodine and an acid selected from the group consisting of hydrochloric, sulphuric, and nitric acids, treating the thus wetted photographic material with a hypo solution, thereafter immersing it in hot water, thereby removing the emulsion layer and forming by the combined action of said acid, hypo, and hot water, a substantially evenly distributed screen-like corrugation on the antihalation layer of said transparent base.
2. Process of manufacturing a screen which comprises the steps of wetting a photographic material consisting of a gelatinous antihalation layer and a gelatinous photographic emulsion layer on a transparent photographic base, said emulsion layer being more easily soluble than said antihalation layer, with an aqueous oxidizer solution containing formaldehyde and an acid selected from the group consisting of hydrochloric, sulphuric, and nitric acids, immersing the photographic material thus treated first in hypo and then in hot water, thereby removing the emulsion layer and forming by the combined action of said oxidizer, hypo, and hot water a substantially evenly distributed screen-like corrugation on the antihalation layer on said transparent base, immersing the thus pretreated screen-like photographic material in glycerine, and enclosing it between two transparent layers in such a manner as to keep it continuously wetted with glycerine.
3. A process of simultaneously forming a screen on the surface of the light sensitive gelatinous emulsion of photographic material for black and white and especially color separation pictures, and correcting the transparency of the entire picture, comprising treating the outer surface of said emulsion after exposure and photographic development with an oxidizer bath comprising at least a halogen, and formaldehyde and also an acid selected from the group consisting of hydrochloric, sulphuric, and nitric acids, thereby simultaneously correcting the transparency of the entire picture and forming a screen-like corrugation in and on said emulsion layer, said screen-like corrugation comprising substantially equally disposed opaque and transparent screen portions, said opaque screen portions being differently blackened in accordance with the light intensity reflected from corresponding portions of the picture taken or printed, and said transparent screen portions being substantially equally transparent throughout the entire photographic picture.
4. A process of simultaneously forming a screen

and correcting the transparency of a picture, as claimed in claim 3, wherein the halogen is iodine.

5. A process of producing a screen on a transparent base having a gelatinous emulsion layer thereon, comprising the step of corrugating the outer surface of said gelatinous emulsion layer by treatment with an oxidizer solution comprising formaldehyde and a halogen and also at least an acid selected from the group consisting of hydrochloric acid, sulphuric acid and nitric acid.

6. A process of producing a screen, as claimed in claim 5, wherein the halogen is iodine.

7. A process of producing a screen comprising corrugating the outer surface of a gelatinous antihalation layer provided on a transparent base by treatment with an oxidizer comprising formaldehyde and a halogen and also an acid selected from the group consisting of hydrochloric, sulphuric and nitric acids.

8. A process of producing a screen, as claimed in claim 7, wherein the halogen is iodine.

9. A method of producing a damp screen comprising the step of corrugating the outer surface of a gelatinous antihalation layer on a transparent film by treatment with an oxidizer comprising formaldehyde, iodine, and an acid selected from the group consisting of hydrochloric, sulphuric and nitric acids, and keeping the thus corrugated antihalation layer permanently wetted with glycerine.

10. Method of treating a photographic material comprising a transparent film provided with a gelatinous emulsion on said film, comprising the steps of partly opaquing said emulsion in accordance with a color component of a photographed picture, and corrugating said emulsion by treatment with an oxidizer comprising formaldehyde and at least a halogen and also an acid selected from the group consisting of hydrochloric, sulphuric, and nitric acids, said oxidizer treatment correcting the transparency of the entire picture and simultaneously resulting in a screen-like corrugation of said emulsion layer, said screen-like corrugation comprising substantially equally distributed opaque and transparent screen portions, said opaque screen portions being differently blackened in accordance with the light intensity reflected from corresponding parts of the picture taken or printed and said transparent screen portions being substantially equally transparent throughout the entire photographic picture.

11. Method of treating a photographic material, as claimed in claim 10, wherein the halogen is iodine.

12. Method of treating a photographic picture comprising a transparent base, an exposed and photographically developed galatinous emulsion on one side and a gelatinous antihalation layer on the other side of said base, said method comprising the steps of wetting the outer faces of said layers with an oxidizer comprising formaldehyde

and at least a halogen and also an acid selected from the group of hydrochloric, sulphuric and nitric acids, thereafter treating said layer faces with a hypo-solution and cold water and thereafter drying them, said combined oxidizer, hypo and cold water treatment forming a screen-like corrugation on said outer faces of both layers and correcting simultaneously the transparency of the picture on said emulsion layer.

13. Method of treating a photographic picture, as claimed in claim 12, wherein the halogen is iodine.

14. Method of treating a photographic picture comprising a transparent base, an exposed and photographically developed galatinous emulsion on one side and a gelatinous antihalation layer on the other side of said base, said method comprising the steps of wetting the outer faces of said layers with an oxidizer comprising formaldehyde and at least a halogen and also an acid selected from the group of hydrochloric, sulphuric and nitric acids, thereafter treating said layer faces with a hypo-solution and cold water, thereafter drying them, then immersing the thus pre-treated photographic picture in glycerine, and finally enclosing it between two transparent layers in such a manner as to keep it continuously wetted with glycerine, said combined oxidizer, hypo and cold water treatment forming a screen-like corrugation on said outer faces of both layers and correcting simultaneously the transparency of the picture on said emulsion layer and said glycerine treatment causing difference in transparency of said layers.

15. Method of treating a photographic picture, as claimed in claim 14, wherein the halogen is iodine.
